United States Patent Office.

WILLIAM W. MARTIN, OF ALLEGHENY CITY, PENNSYLVANIA.

Letters Patent No. 73,908, dated January 28, 1868.

IMPROVEMENT IN SPIKE.

The Schedule referred to in these Letters Patent and making part of the same.

TO ALL WHOM IT MAY CONCERN:

Be it known that I, WILLIAM W. MARTIN, of the city and county of Allegheny, in the State of Pennsylvania, have invented a new and useful Improvement in Spikes for Rails of Railways; and I do hereby declare that the following is a full and exact description thereof, reference being had to the accompanying drawings, and to the letters and figures of reference marked thereon.

It is a fact well known to all who are skilled in the science of railroad-engineering, that the action of the car-wheels, when in motion, causes a vibrating and undulating motion of the rails, and that this vibration and undulatory motion of the rails will loosen the spikes, and free them from their hold in the sleepers or "cross-ties" of the rails, thereby making the spikes inefficient for the purpose of holding the rails firmly to their place on the sleepers or "cross-ties."

It is a fact also well known, that in driving nails or spikes into wood, if the fibre of the wood is cut at right angles to the longitudinal plane of the fibre, and if the plane of the long diameter of the nail or spike is on a line with the longitudinal plane of the fibre of the wood, the nail or spike can be driven into the wood without splitting it, and that the cut ends of the fibre will drag downwards with any rough or uneven surface of the nail or spike, and again assume its normal position, as near as the nail or spike will allow it, and that in proportion to the tendency of the fibre of the wood to keep on a direct line with its growth, will be the hold of the wood on the nail or spike. Now it has been the aim and desire of those skilled in railroad-engineering to obtain a spike for holding the rails to their sleepers or "cross-ties," that will compensate for and resist the vibrating and undulating motion of the rail.

Now, the nature of my invention consists in constructing a spike that is adapted to the natural tendency of the fibre of the wood, and will cut the fibre of the wood at right angle to the longitudinal plane of said fibre, and at right angle to the long diameter of the body of the spike; and also in providing two sides of said spike with a number of inclined projections resembling sections of screw-threads, which are so arranged with relation to each other, and to the body of the spike, that they will perform all the functions common to a screw, and to barbs on a spike.

To enable others skilled in the art to make and use my improvement, I will proceed to describe its construction and operation. In the accompanying drawings, which form part of my specification—

Figure 1 represents a side elevation of my improvement in spikes.

Figure 2 is an edge view of the same.

Figure 3 represents a transverse section of the spike, when cut through at line x^2 .

Figure 4 represents a transverse section of a rail, and a longitudinal section of the spike, and a sleeper or "cross-tie."

I construct the body A and head B of the spike in the ordinary form, and by the usual means, but, in addition thereto, provide the two edges x and x^1 with a number of inclined projections, D, which resemble sections of screw-threads. The entering-point, C, of the spike, is made in the form of a wedge. The cutting-edge of the point of the spike is formed by beveling the lower part of the edges x and x^1 .

As the form of the spike is clearly shown in the accompanying drawings, and its construction will be readily understood by the skilful mechanic, therefore, without further description of its construction, I will proceed to describe its operation. In securing down rails for railways, I drive the spike into the sleeper or "cross-tie" in the ordinary manner, and with the usual means, taking care to set the spike so that the cutting-edge of its point will cut the fibre of the wood at right angle to its growth, that is to say, the plane of the long diameter, indicated by line 2 of the body of the spike, must be parallel to the longitudinal plane of the fibre or growth of the wood. The spike, in entering wood, cuts its fibre at right angle, and the under side of the projections being inclined or bevelled, and arranged lengthwise on an oblique line to the longitudinal plane of the spike, it will, with its projections D, drive into the wood without breaking the fibre, which will, after the spike is driven to the desired depth, assume the line of its growth, as near as the form of the spike will allow, and thereby cause the wood to hug closely around the body A and projections D of the spike, thus giving to the projections D all the advantages of barbs on a spike, without the disadvantage of tearing and breaking of the fibre of the wood, which tearing and breaking is common to the barbed spike. In removing the spike from the

sleeper or "cross-tie," I take a suitable lever or other means, and turn the spike around in the manner for removing wood-screws.

By constructing spikes in the form herein described, I obtain all the advantages that are common to the screw or barbed spike, without liability, when driving it, of tearing or breaking the fibre of the wood, and which will not turn, twist, nor become loose by the vibrating or undulating motion of the rails.

It will be observed that by making the sides x^3 and x^4 flat, and parallel with each other, and the other two sides or edges, x and x^1 , in the form of arcs of a circle, the curvilinear measurement of which is greater than the measurement of the parallel sides x^3 and x^4 , and the measurement of the chords of said arcs about equal to the measurement of said parallel sides, the spike thus formed will have all the properties of a spike, the body of which is square, when viewed in cross-section, which form experience has demonstrated to be the best for strength and holding combined. Now be it observed that by my form of spike, viewed in cross-section, as clearly shown in fig. 3, I obtain all the advantages of the ordinary cut nail, for driving into the wood, the strength of the square spike, and the holding quality of the barbed spike.

I wish it clearly understood that I do not claim "a screw-spike," or a spike having two sides or edges corrugated, but

What I claim, is—

A new article of manufacture, viz, a spike, constructed and operating substantially as herein described and for the purpose set forth.

W. W. MARTIN.
